(57) **CLAIM**

The ornamental design for a boot upper or portion thereof, as shown and described.

DESCRIPTION

The present application is related to U.S. Design Patent Application No. 29/655,417, entitled boot upper, and to U.S. Design Patent Application No. 29/655,420, entitled patterned boot upper, both filed concurrently herewith, the entire disclosures of which are incorporated herein by reference.

FIG. 1 is a front perspective view of the boot upper according to my design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Broken lines are environmental only and form no part of the claimed design.

The short, even-length dashed broken lines represent stitching that forms part of the claimed design.
